UNITED STATES PATENT OFFICE

GEORGE W. SCHULZ, OF CLEVELAND, OHIO, ASSIGNOR TO YAWMAN & ERBE MANUFACTURING CO., OF ROCHESTER, NEW YORK, A CORPORATION OF NEW YORK

EXTENSIBLE DESK TOP

Application filed November 21, 1928. Serial No. 320,780.

This invention relates to an extensible top for furniture construction, and it pertains more particularly to a commercial bookkeeper's desk adapted to be used with a bookkeeping machine and portable posting tray so that the bookkeeper may expeditiously make his entries, consult various card indexes, etc. with comfort and convenience. In modern bookkeeping practice it is desirable to provide each bookkeeper with a complete "plant" in which the desk must preferably be compact and relatively small.

An object of this invention is to provide such a desk with an extensible top whereby adequate space may be provided for sorting checks, bills and other papers, examining large and bulky ledgers, etc.

A further object is to provide an extensible top in which the movable portion is flush with the fixed portion when in the extended position.

A further object is to provide improved guide and supporting means for the movable top portion whereby it may be readily moved into the closed or extended positions.

Another object is to provide a commercial bookkeeper's desk top with a telescoping guard rail which also serves to prevent the front of the extended top from tipping forward.

Another object is to provide properly aligned flanges on the fixed and extensible portions whereby they fit snugly in an extended position and whereby the inclined flange also serves as a guide when the desk top is closed.

Other objects will be apparent as the detailed description of my invention proceeds.

In the accompanying drawings wherein similar parts are represented by like reference characters throughout the several views, Fig. 1 is a perspective of my improved bookkeeper's desk showing the top in closed position and showing the relative position of the bookkeeping machine.

Fig. 2 is a similar perspective showing the desk top in extended position.

Fig. 3 is a vertical section showing the desk top in open position, and

Fig. 4 is a similar vertical section showing the desk top in closed position.

Referring to Figs. 1 and 2, a desk 10 is provided with suitable drawers 11 and movable top 12. This top is preferably provided with an extension 13 for utilizing the space between the desk and the bookkeeping machine, a cut-away portion 14 being provided to allow the carriage 15 of the bookkeeping machine 16 to travel therein.

When the movable top portion 12 is extended, the fixed top portion 17 is exposed (see Fig. 2). The fixed top portion is provided with end guard rails 18 and 19 and with a rear guard rail 20. The tops of the end guard rails are formed into rebent flanges 21 and 22 respectively. End guard rails 23 and 24 on movable top member 12 cooperate with guard rails 18 and 19 when the top is in extended position, to form an enclosure for the top of the desk and to prevent papers or cards from being blown away or dislodged. The guard rails 23 and 24 telescope in the space between guard rails 18 and 19 and their respective rebent flanges 21 and 22 when the movable top is closed. A guard rail 25 is preferably provided for the extended portion 13 of the movable top member, this guard rail being an extension of the guard rail 24.

This arrangement of guard rails not only presents a neat and attractive appearance, but it serves as a reinforcement to prevent the top from tipping forward due to a downward force on the extended portion of top member 12.

In Fig. 3, the details of construction are shown with more particularity, but it is understood that this embodiment is illustrative only and that various modifications will fall within the scope of my invention.

The sheet metal stamping 26 may be the top of a sheet metal desk or it may be a detachable member by which the slidable top may be mounted on any existing desk, the downwardly extending flange 27 being provided with apertures 28 for this purpose. The front of the stamped metal sheet 26 is preferably provided with downwardly bent flanges for reenforcing it and for simulating

thickness and giving it a more solid appearance. A downwardly bent flange at the rear of this sheet abuts against and is secured to the rear guard rail 20. The fixed portion of the extensible top structure is mounted on plate 26 and it preferably comprises a sheet metal plate 29 having a flange abutting against guard rail 20 and a rebent flange resting on plate 26. A suitable desk topping material 30, such as linoleum, is mounted on plate 29 and is held thereon by a metal sheet 31 which acts as a moulding strip 31a for protecting the edge of the linoleum and which acts as a guide or track 31b for the rollers supporting the movable portion, as will hereinafter be pointed out.

This reinforcing plate 31 is provided with an obtuse flange 31c to which is secured the front end of plate 29. At the lower end of the obtuse flange there is a slight horizontal portion extending to and abutting against a guide rail 36.

The movable top portion also consists of a metal plate 29' upon which is mounted suitable covering 30' of linoleum or other desk topping material. Secured to the plate 29' are brackets 32 and 33 in which are journaled rollers 34 and 35 for supporting and slidably mounting the extensible portion of the top. Roller 34 is adapted to travel on a guide rail 36, the outer end of this guide rail having an inclined portion 36a of the same slope as the obtuse flange 31c. A locking member 37 fixed to guide rail 36 co-acts with roller 35 when the top is extended for preventing a weight on the overhanging top from rotating the movable portion about roller 34. The rebent flanges 21 and 22 co-operate with guard rails 23 and 24 to prevent this end of the movable top from flying up when the roller is not engaged by the locking member 37. A stop member 38 limits the outward movement of the extensible portion and allows a certain degree of flexibility for the locking member 37.

The front of the extensible top portion is preferably provided with a downwardly extending rebent flange 39 to simulate thickness, to which is secured a suitable moulding 40 for overlying and protecting the edge of the linoleum. The rear part of the extensible top portion is provided with an acute angle moulding strip 41, the upper leg of which protects the edge of the linoleum and the lower edge of which abuts against the obtuse angle flange 31c on the fixed portion of the top. Since the angles of the flange 31c and the moulding 41 are supplementary, these elements will fit closely together and the top surface of the fixed and movable portions will lie in the same plane when the top is extended.

The operation of my improved device is apparent from the above description: When the movable top is pushed rearwardly roll-

ers 34 and 35 travel upwardly on the inclined surfaces 36a and 31c to elevate movable top 12 above fixed top 17 and to bring guard rails 23 and 24 to the top of guard rails 18 and 19. When the movable portion is at the limit of its inward motion the fixed portion is entirely covered.

While I have herein illustrated a specific embodiment of my invention, it will be understood by those skilled in the art that various changes and modifications may be made without departing from the principle and scope of my invention as set forth in the appended claims.

I claim:

1. An extensible furniture top construction comprising a fixed portion and a movable portion, an inclined flange on said fixed portion, a supplementary flange on the movable portion, guide means associated with said fixed portion, rollers carried by said movable portion and cooperating with said guides to cause the supplementary flanges to register when the top is in extended position, means for locking the inner end of the movable portion in extended position, said guide means causing the movable portion to cover the fixed portion when the top is in closed position.

2. An extensible furniture top construction comprising two relatively movable elements, one of which is fixed, complementary inclined flanges on said elements, one adapted to rest on the other when the top is in extended position, guide means associated with said fixed element, means carried by said movable element and cooperating with said guides for adjustably supporting said movable element, a locking member on said fixed element engageable with said means for limiting the extending movement of said movable element; and means directing said movable element to a position to cover the fixed element when the top is in closed position.

3. In furniture construction, a stationary top, end and rear guard rails fixed to said top, a rebent flange on said end guard rails, a movable top, guide means associated with said fixed top, means carried by said movable top for coacting with said guide means whereby the movable top covers the fixed top when closed and is positioned in the same horizontal plane with it when extended, and end guard rails on said movable top adapted to be a continuation of said first mentioned guard rails in extended position and to telescope with said guard rails and their rebent flanges in closed position.

4. In furniture construction, a stationary top, end and rear guard rails fixed to said top, a rebent flange on said end guard rails, a movable top, guide means associated with said fixed top, means carried by said movable top for coacting with said guide means whereby the movable top covers the fixed top

when closed and is positioned in the same horizontal plane with it when extended, said fixed and movable tops comprising inclined complementary flanges, one of which is disposed and adapted to rest on the other when the tops are extended into the same horizontal plane, and end guard rails on said movable top adapted to be a continuation of said first mentioned guard rails in extended position and to telescope with said guard rails and their rebent flanges in closed position.

5. An extensible furniture top construction comprising a fixed portion and a movable portion, an obtusely inclined flange on said fixed portion, and a supplementary acute angle portion on the movable portion, guide means associated with said fixed portion, mounting means carried by said movable portion and coacting with said guide means to cause the supplementary angle portions to rest on the other when the top is in extended position, a locking member on said fixed element engageable with said 10 mounting means for limiting the extending movement of said movable portion, and means cooperating with said inclined flanges and said mounting means for directing said movable portion to a position to cover the fixed portion when the top is in closed position.

In witness whereof, I hereunto subscribe my name this second day of November, 1928.

GEORGE W. SCHULZ.
